HIS ATTORNEY.

UNITED STATES PATENT OFFICE.

BERNHARD EHRLICH, OF VIENNA, AUSTRIA-HUNGARY.

TELEPHONE ATTACHMENT.

No. 814,680.

Specification of Letters Patent.

Patented March 13, 1906.

Application filed May 3, 1905. Serial No. 258,609.

To all whom it may concern:

Be it known that I, BERNHARD EHRLICH, bookkeeper, a subject of the Emperor of Austria-Hungary, residing at II Obere Donaustrasse 65, Vienna, Austria-Hungary, have invented a new and useful Improvement in Telephone Apparatus; and I do hereby declare the following to be a full, clear, and exact description of the same.

10 The object of this invention is to provide a hygienic protective attachment for telephone apparatus; and it consists in improvements in that class of such devices as are provided with a plurality of separately-removable leaves or sheets placed one upon another and with antiseptic netting applied to the opening in said attachment.

Referring to the accompanying drawings, Figure 1 is a vertical section through a telephone-receiver and through the attachment secured thereto. Fig. 2 is a rear view of such attachment removed, and Fig. 3 is a front view of the plate or slide having germicidal netting over the sound-opening.

25 The attachment (shown secured upon the receiver *h*) consists of a rigid body-piece or base *c*, provided with sheet-metal or other clasps or clips *g* to be bent over or otherwise engage the edge of the receiver, and is provided with a plurality of separately-removable leaves or sheets *b*, placed one upon another and secured together and to the base *c* by pasting or otherwise. The pile of leaves or sheets is provided with a central opening, and the base *c* is also provided with an opening with which that first named registers. Upon its back the body-piece is provided with attached parallel guides *m*, made of sheet metal or other material, between which a 35 strip or plate *k*, (see Fig. 3,) of cardboard or other material, is slidably and removably held. The slideable strip or plate is provided with an opening, and a piece of netting *f*, treated with germicidal substance, is secured 40 over said opening. When the plate *k* is slid into place, the opening thereof coincides with the openings in the block and in the receiver.

45 The arrangement described prevents all danger of infection when using the telephone, as by tearing off a sheet of paper every time the telephone is used a fresh sheet absolutely clean and non-infected is provided, while the

netting *f* absorbs any contagious material there may be and renders the same innocuous.

55 What I claim is—

1. An attachment for telephones, consisting of a rigid body-piece and a plurality of leaves or sheets placed one upon another and secured to the body-piece, said attachment having an opening extending therethrough, and a removable plate or slide carrying netting treated with germicidal substance placed over the opening aforesaid and slidably engaging the rigid body-piece.

65 2. An attachment for telephones, consisting of a rigid body-piece and a plurality of separately-removable leaves or sheets placed one upon another and secured to the body-piece, said attachment having an opening extending therethrough, and a removable plate or slide carrying netting treated with germicidal substance placed over the opening aforesaid and slidably engaging the attachment.

70 3. An attachment for telephones, consisting of a rigid body-piece and a plurality of separately-removable leaves or sheets placed one upon another and secured to the body-piece, said attachment having an opening extending therethrough, a removable plate 75 carrying netting treated with germicidal substance placed over the opening aforesaid and metallic overlapping portions securing the plate and attachment together.

80 4. An attachment for telephones, consisting of a rigid body-piece and a plurality of separately-removable leaves or sheets placed one upon another and secured to the body-piece, said attachment having an opening extending therethrough, a pair of guides carried 85 by the back of the attachment, and a removable plate or slide slidably engaged with the guides aforesaid, said plate or slide carrying netting in line with the opening through the attachment and treated with germicidal substance.

85 In testimony whereof I have signed this specification in the presence of two subscribing witnesses.

BERNHARD EHRLICH.
